(57) **CLAIM**

The ornamental design for a chainsaw clearing tooth, as shown and described.

DESCRIPTION

FIG. 1 is a right-side perspective view of the chainsaw clearing tooth;

FIG. 2 is a left-side perspective view of the chainsaw clearing tooth;

FIG. 3 is a right-side elevation view of the chainsaw clearing tooth;

FIG. 4 is a top plan view of the chainsaw clearing tooth;

FIG. 5 is a left-side elevation view of the chainsaw clearing tooth;

FIG. 6 is a bottom plan view of the chainsaw clearing tooth.

FIG. 7 is a front elevation view of the chainsaw clearing tooth;

FIG. 8 is a rear elevation view of the chainsaw clearing tooth; and,

FIG. 9 is a side view of the chainsaw clearing tooth as part of a chainsaw chain.

The broken lines shown in the drawings are for the purpose of illustrating environmental matter and unclaimed matter and form no part of the claimed design.

1 Claim, 4 Drawing Sheets
